CLAIM

The ornamental design for a glove with pocket, as shown and described.

DESCRIPTION

FIG. 1 is a perspective view of the glove with a pocket showing an embodiment of my new and ornamental design; FIG. 2 is a perspective view thereof, shown in a configuration of use;

FIG. 3 is a front view of FIG. 1;

FIG. 4 is a front view thereof, shown in a configuration of use;

FIG. 5 is a front view of a left hand embodiment of FIG. 4, shown in a configuration of use;

FIG. 6 is a rear side view of FIG. 1;

FIG. 7 is a left side view thereof;

FIG. 8 is a right side view thereof;

FIG. 9 is a top side view thereof; and,

FIG. 10 is a bottom view thereof.

This application contains two types of broken lines: dash-dash broken lines and dash-dot broken lines. The dash-dash broken lines represent portions of the disclosed article and do not form a part of the claimed design. The dash-dot broken lines represent environmental structure and do not form a part of the claimed design.
